I. GONYK

DISTRIBUTING DEVICE FOR SOLID SOAP

Filed Feb. 16, 1927

Inventor,
Ignacy Gonyk,
By Henry Orth Jr. att.

UNITED STATES PATENT OFFICE.

IGNATZ GONYK, OF LJUBLJANA, KINGDOM OF THE SERBS, CROATS, AND SLOVENES.

DISTRIBUTING DEVICE FOR SOLID SOAP.

Application filed February 16, 1927, Serial No. 163,702, and in Germany June 17, 1926.

My invention consists in a distributing device for solid soap comprising a movable container for a soap stick, from which small sheets or slices may be cut, while the soap stick is advanced for a short way on account of its own weight each time when a slice of soap is cut off therefrom. The device is provided with means for cutting off slices of soap from the bar when the container is moved sideways over said cutting element which preferably consists in a knife having a slightly curved blade. Further particulars of the device according to my invention will appear from the following specification.

15 The accompanying drawing shows by way of example an embodiment of the distributing device according to my invention.

Fig. 1 is a front view of the device;

20 Fig. 2 is a section along line A—B of Fig. 1; Figs. 3 to 6 illustrate details of the device shown in Figs. 1 and 2.

The soap distributor device comprises a back plate *a* to which is fixed a sheet *b* which partly covers the plate *a*. From said sheet *b* extending at right angles thereto is an upper element *c* and a lower element *d*. On the upper element *c* a tube-shaped soap container *f* is pivotally mounted by means of a bolt and eye connection. For this purpose the top *h* of the container *f* carries a fork-shaped projection *g* which is provided with eyes *i* and *j*, whereas in the element *c* there is an eye *k* which is located between eyes *i* and *j*, the connection between said eyes being made by means of a bolt *l*.

35 The top *h* is provided with a laterally projecting slotted portion *m* into which a screw thread is cut so as to engage with a set-screw *n* the square head of said screw extending into a hole *p* of the element *c*; the screw-collar *q* comes to rest on two ledges *r* bent inwardly from the element *c* (Fig. 5). The set-screw *n* is enclosed in the part between the projection *m* and the ledges *r* by a spring *s* abutting on said parts *m* and *r*. The screw *n* may be adjusted by means of a key *t*.

40 The soap container carries a handle knob *u* and at its bottom end a guide element *v* guided with its lower flange-shaped part *w* (Fig. 3) in the element *d* forming a frame. The innermost end of said element *d* carries a knife *x* having a segment-shaped blade. Below the knife *x* the bottom of element *d* is provided with a circular opening *d'* and below this opening with a delivery tray or chute *y* the bottom of which is inclined downwardly to-

wards the front part and has a semicircular cutting on the front edge and on both sides of said cutting up-turned tongues *z* are provided.

Before use the set-screw *n* is loosened by 60 means of key *t* so as to allow the collar *q* to pass through the opening *p*. The container *f* may then be swung by means of the handle knob *u* around the bolt *l* so that it will be free of the edge of part *d* thereby freeing the bottom end of the container, which is now ready to receive a bar of soap to be inserted into the container from below. Thereupon the container is pushed back to a position in which the flange *w* is in alignment with the 65 outer edge of the element *d* and screw *n* is tightened and again takes the position shown in Figs. 1 and 2, the collar *q* being once more resting upon the ledges *r* on account of the action of the spring *s*. 75

The soap bar owing to its own weight rests on element *d* that is to say it projects beyond the bottom edge of the tubular container for the same length as the guide piece *v*. If the casing is pressed by means of knob *u* toward 80 plate *a* into the position shown in dotted lines in Fig. 2, a slice of soap will be cut off by means of knife *x* and will fall down through the circular opening *d'* to the chute *y* from whence it slides down until it is stopped by 85 the tongues *z*. The semicircular cutting at the front end of the chute allows easy gripping of the slice of soap.

The above described device may easily be combined, if desired, with a coin operated 90 actuating mechanism of a known kind by providing a locking device which usually prevents the pivot-movement of tube *f* and will permit the actuation of the same only after a coin has been thrown into the mechanism. 95

What I claim is:

1. A soap dispensing device, comprising a soap container pivotally mounted at one end, a fixed member normally closing the free end of the container for supporting the soap carried by the latter, a knife mounted between the fixed member and the path of the free end of the container to sever the soap supported on said member during the movement of the container in one direction, and means connected with the pivoted end of the container for limiting the normal movement of the container relative to the fixed member. 100

2. A soap dispensing device comprising a 110 tubular soap container, a support, means on one end of the container pivotally connecting

the latter to the support, a fixed member normally closing the free end of the container, for supporting the soap in the latter, means at the pivoted end of the container for limiting 5 the oscillatory movement of the latter relatively to the fixed member, and a knife interposed between the fixed member and the path of movement of the free end of the container.

3. A soap dispensing device comprising a 10 support, a tubular soap container pivotally connected thereto at one end, a fixed plate below the free end of the container for supporting the soap therein, a knife above said plate, means yieldingly holding the free end 15 of the container normally in front of the knife, and means for limiting the oscillatory movements of the container relatively to the fixed plate.

4. A soap dispensing device comprising a 20 support, a tubular soap container pivotally connected at one end to the support, means at the pivoted end of the container for yieldingly holding the latter in an inclined position, a fixed soap supporting member below 25 the free end of the container, a knife on the soap supporting member below the path of the free end of the container, and means connecting the support and container to normally limit the movement of the latter relative to the soap supporting member.

5. A soap dispensing device comprising a horizontal support, a tubular soap container pivotally connected at its upper end to the support, a knife carrying element closing the 35 free end of the container and supporting the soap carried by the latter, a forked member on the upper end of the container, and a set-screw connecting the support and forked member for limiting the movement of the 40 container to correspond with the length of the knife carrying element.

6. A soap dispensing device comprising a 45 supporting plate, a tubular soap container pivotally connected at its upper end to the support, a knife carrying element closing the

free end of the container, a lateral projection on the pivoted end of the container, a set-screw in said projection extending through an opening in the supporting plate and having a collar formed thereon, and ledges 50 formed on the supporting plate to engage the collar to limit the outward swing of the container relative to the knife carrying element.

7. A soap dispensing device comprising an upper supporting element having an aperture therein, a tubular soap container pivotally connected at its upper end to said element, a knife carrying element closing the free end of the container, a lateral projection on the pivoted end of the container, a set-screw 55 in said projection extending through the aperture, ledges on the supporting element projecting into said aperture, a collar on the set-screw adapted to engage the ledges to limit the outward movement of the container relative to the knife carrying element, and means whereby the set-screw may be rotated to free the collar from the ledges to permit the container to be swung clear of the knife-carrying element.

8. A soap dispensing device comprising an upper supporting element having an aperture therein, a tubular soap container pivotally connected at its upper end to said element, a knife carrying element closing the 75 free end of the container, a lateral projection on the pivoted end of the container, a set-screw in said projection extending through the aperture, ledges on the supporting element projecting into said aperture, a collar on the set-screw adapted to engage the ledges to limit the outward movement of the container relative to the knife carrying element, and a spring surrounding the screw between the supporting element 80 and the lateral projection to automatically swing the container.

In testimony that I claim the foregoing as my invention I have signed my name.

IGNATZ GONYK.
